UNITED STATES PATENT OFFICE.

GEORGE J. METZGER, OF ROCHESTER, NEW YORK.

DESIGN FOR A HAT SWEAT-BAND.

SPECIFICATION forming part of Design No. 29,566, dated November 1, 1898.

Application filed August 22, 1898. Serial No. 689,181. Term of patent 7 years.

To all whom it may concern:

Be it known that I, GEORGE J. METZGER, a citizen of the United States, residing at Rochester, in the county of Monroe and State of New York, have invented and produced a certain new and original Design for Hat Sweat-Bands; and I do declare the following to be a full, clear, and exact description of the invention, such as will enable others skilled in the art to which it appertains to make and use the same.

The invention has relation to a new and original design for a hat sweat-band; and it consists of a hat sweat-band of the configuration shown in the accompanying drawings, in which—

Figure 1 is a perspective view, and Fig. 2 a vertical sectional view.

In the drawings, 1 denotes an annular band having near its lower edge an annular row of perforations 2.

3 denotes the outer parallel band, having a row of perforations 4.

5 denotes the annular horizontally-extended web, having an annular row of perforations 6, 25 and 7 denotes bails which straddle said bands and have their lower ends joined to the edges thereof, the outer band 3 being of less height than the inner band 1.

What I claim is—

The design for a hat sweat-band as herein shown and described.

In testimony whereof I have hereunto set my hand in presence of two subscribing witnesses.

GEORGE J. METZGER.
